CLAIM

The ornamental design for a bone drill bit for bone fasteners, as shown and described.

DESCRIPTION

FIG. 1 is a perspective view of a bone drill bit for bone fasteners, showing our new design;

FIG. 2 is a side elevational thereof, taken from the left side of FIG. 4;

FIG. 3 is a top plan view thereof;

FIG. 4 is a front elevational view thereof; and,

FIG. 5 is a rear elevational view thereof.

FIGS. 1, 2 and 3 have been shown broken away because the article is of indefinite length.
